[57] CLAIM

The ornamental design for an electrical plug housing, as shown and described.

DESCRIPTION

FIG. 1 is a perspective view of an electrical plug housing showing my new design;

FIG. 2 is a front side elevational view thereof;

FIG. 3 is a top plan view thereof, the bottom view being identical except for the pin configuration;

FIG. 4 is a right side elevational view thereof, the left side being identical;

FIG. 5 is a rear side elevational view thereof;

FIG. 6 is a perspective view of the electrical plug housing showing a second embodiment of my new design attached to an electrical receptacle;

FIG. 7 is a perspective view thereof;

FIG. 8 is a front elevational view thereof;

FIG. 9 is a top plan view thereof, the bottom view being identical except for the pin configuration;

FIG. 10 is a right side elevational view thereof, the left side being identical; and,

FIG. 11 is a side elevational view thereof.

The broken line showing of the electrical plug in FIG. 6 and the electrical cords in FIGS. 1, 3, 4-7 and 9-11 together with the electrical contacts in FIGS. 1-4 and 6-10 is included for the purpose of illustrating environmental structure only and forms no part of the claimed design.
